[57] CLAIM

The ornamental design for a vehicle grille, as shown and described.

DESCRIPTION

FIG. 1 is a front perspective of a vehicle grille embodying my new design, the front of an automotive vehicle being shown fragmentally to show the environment in which the grille is used;

FIG. 2 is a front elevational view of the grille;

FIG. 3 is a side elevational view thereof, the side opposite being a mirror image of the side shown;

FIG. 4 is a rear elevational view thereof;

FIG. 5 is a top plan view thereof; and,

FIG. 6 is a bottom plan view thereof.
